SWITCH

Marion W. Morris, Logansport, Ind., assignor to
 R-B-M Manufacturing Company, Logansport,
 Ind., a corporation of Indiana

Application July 15, 1933, Serial No. 680,561

2 Claims. (Cl. 173—346)

This invention relates to switches, and more particularly to switches adapted for use in controlling dome lights in vehicles or the like, although it is not to be limited to this specific use.

5 It is desirable in switches of this type, which are subjected to shock and vibration, that a snap mechanism be provided which will positively hold the switch in predetermined position unless it is manually actuated, but the cost of producing such 10 a switch has heretofore been such that it is not capable of manufacture on an economical basis.

Further, it is necessary, especially in switches adapted for use in connection with dome lights and the like, that the switch structure be made as 15 compactly as possible, with a minimum number of parts, in order that it occupy as small a space as possible within the vehicle.

It is an object of the present invention to produce a switch of the type described having a simplified construction which will provide a snap action for maintaining the switch in predetermined position unless manually actuated, and using a minimum number of parts, the switch being capable of assembly within a compact structure.

25 A further object of the invention is to utilize the means for securing the terminal members or lugs of the switch unit in position, as the switch contacts, thereby achieving a simplified and economical construction. In the present invention, 30 ease and accuracy of operation is assured by forming the snap actuating mechanism directly in the switching member, so that manual actuation of the switch operates the mechanism directly, thus reducing the number of parts necessary for 35 producing this action, and providing for direct control of the snap actuating mechanism.

The switch of my invention has an additional 40 advantage in that it can be formed as a part of the dome light structure, when used in this connection, or as a separate switch device, without in any way modifying its simplicity of operation and design. In connection with this feature, I have provided a structure which, when formed as a part of the dome light structure, requires 45 only one switch contact in order to effect operation of the light.

Other objects and advantages of the present invention will appear more fully from the following detailed description, which, taken in connection with the accompanying drawing, will disclose to those skilled in the art the particular construction and operation of my invention.

In the drawing:

Figure 1 is a plan view of a dome light structure with the switch embodied therein;

Figure 2 is a plan view of the switch structure as embodied in Figure 1;

Figure 3 is a sectional view taken substantially on the line 8—8 of Figure 2;

Figure 4 is a sectional view taken substantially on the line 9—9 of Figure 3; and

Figure 5 is a front elevational view of the switch structure shown in Figure 2.

In the embodiment of my invention shown in Figures 1 to 5, I have illustrated the application 10 of the switch of the present invention to a dome light structure, wherein the switch is directly embodied in the dome light housing, and forms a part thereof.

The dome light structure is indicated generally 15 in Figure 1 by the reference numeral 30, comprising a plurality of concentric flanged portions formed of metal or the like. Disposed upon an inner normally extending flanged portion of the housing I provide a socket structure, indicated at 20 31, which is riveted to the flange at 32, and which has an upstanding portion projecting toward the central part of the housing and provided with a lamp-receiving portion indicated at 34 for receiving the base 35 of a small filament 25 lamp 36. The base 35 of the lamp is adapted to extend through an opening in the socket 31, and carries a projecting contact portion 37 passing through an opening 38 formed in the flange of 30 the housing. The two contacts of the filament 35 of the lamp 36 are therefore engaged by the up-standing portion 34 of the socket member 31, and by contact with the inner tip 37 at the base portion 35 of the lamp.

The switch of the present invention, when embodied in this construction, comprises a generally 35 rectangularly shaped housing indicated at 40, which is provided with two curved flange portions 41, having suitable openings 42 therein adapted to receive the rivets 32 which secure the socket 40 member 31 in position with respect to the flange. This rivet engagement provides a switch which is structurally designed so as to prevent interference with radio circuits which may be installed 45 in the vehicle in which the switch is mounted. It has been found that solder joints for the same purpose are undesirable in that they produce 50 noises in the operation of such a radio system. The switch is disposed beneath the flange portion 30 of the housing, and has a switch actuating rod or member 44 adapted to project through an opening or slot 45 formed in the surface of the flange member. The rod 44 is held in position 55 within the housing 40 by means of opposed pairs of struck-out bearing portions indicated at 46 55

and 47 which are adapted to form bearing supports for a pin 48 upon which the switch member 44 is mounted. This provides rocking action about the pin 48 for the member 44, the inner end of the member 44 projecting within the housing 40.

The housing 40 is provided with a plurality of upstanding ears or lug members 50 which are adapted to engage in suitably notched portions of an insulating member 51 secured over the top 10 of the housing. The lugs 50 are bent over into engagement with the upper surface of the member 51, and serve to secure the member 51 in fixed position upon the housing 40, thus enclosing the housing and switch mechanism.

15 Mounted upon the member 51 are a pair of terminal lug members indicated at 52 and 53. The lug member 52 is adapted to be secured to the insulating member 51 by means of a rivet 54, which extends through the member, and has 20 its upper end spun over, as shown at 55, for securing the lug in position. The lug 52 is also provided with a downwardly punched portion indicated at 56, which serves to align the lug with respect to the member 51, so that it cannot be 25 moved out of position.

A suitable insulating member 57 is interposed between the member 51 and the lug 52. The rivet 54 has an inner headed portion 58, which is adapted to be secured over a depending contact 30 member indicated at 59, which is interposed between the head 58 and the inner surface of the member 51.

The contact member 59 is provided with an upwardly extending tongue portion 60 which is 35 adapted to align the member 59 in position and prevent its rotation with respect to the rivet 54. The downwardly depending portion of the member 59 is adapted to contact the inner extending contact 37 of the filament bulb 36, to provide the 40 second contact for the bulb. If desired, the member 59 may be curved, or may be made of spring metal in order to effect positive resilient engagement with the lamp contact at all times.

The lug 52 extends downwardly over the side of 45 the housing 40, and is provided with a threaded coupling member 61 for securing a terminal lead to the lug. The member 61 is adapted to thread into the lug 52, and its inner extending end passes through an opening 62 formed in the housing 40.

50 Considering now the lug 53, this lug extends over the upper surface of the member 51, being held in aligned position with respect thereto by means of the downwardly punched portion 64, which engages in a suitable opening formed in 55 the member 51. The lug 53 is adapted to be bent over the edge of the member 51 at the rear thereof, and extends downwardly a sufficient distance to receive a threaded coupling member 65 for securing a terminal lead thereto. The coupling 60 member 65 extends through an opening 66 formed in the housing 40, in the same manner as described in connection with the coupling member 61. This disposition of the coupling members effects a considerable saving of space.

65 A suitable insulating member, preferably of fiber or other insulating material, is interposed between the lug 53, and the members 51 and 40. This insulating member is indicated at 67. The lug 53 is held in position by means of the rivet 68, 70 in the same manner as described in connection with the rivet member 54, but the inner end of the rivet 68 is adapted to have a substantially dished inner surface, as indicated at 70, for providing a contact surface for the switch contact 75 plunger head 71.

Considering now in detail the switch actuating mechanism mounted at the inner end of the switch actuating member 44, the inner end of this member is recessed as indicated at 72 in Figure 3. Disposed over the recessed end of the member 44 5 is a plunger member 73, having the substantially hemispherical contact portion 71 adapted to engage the substantially spherical recess 70 formed in the rivet 68. The plunger 73 is adapted to have sliding axial movement with respect to the member 44. A spring member 74 disposed within the recess 72, and bearing at one end against the plunger and at the other end against the member 44, serves to force the plunger 73 outwardly of the member 44. 15

In the operation of the switch, the member 44 is rocked about the pivot 48, and serves to engage the headed end 71 of the plunger 73 either in the recess 70, in order to complete a circuit through the bulb 36, or in the semi-spherical 20 recess 75 formed in the insulating member 51, in which position the plunger 71 is out of contact with the electrical circuit, thus disconnecting the bulb 36. Because of the spring disposed within the member 44, which normally urges the plunger 25 outwardly, a snap action is effected, which serves to maintain the member 44 either in positive engaged position, or in disengaged position, regardless of any shocks or vibration to which the instrument may be subjected. This also provides a 30 positive snap action for preventing the switch from remaining in any intermediate position with respect to the contact 70 or the recess 75.

It will be noted that, although two leads are brought to the switch member, nevertheless only 35 one contact is engaged or disengaged in order to effect actuation of the light. The lead from the terminal lug 52, which is secured to the coupling 40 61, conducts the current through the lug 52 to the depending contact member 59, which engages 45 the lower tip portion of the bulb. Current from this point travels through the filament 76 of the bulb and through the outer surface 35 of the base thereof to the upstanding portion 34 of the socket member 31, and thence through the socket member 31 and the rivets 32 to the flanges 41 of the housing 40. From the housing 40, the current is conducted through the pin 48 and the actuating member 44 to the plunger 73 and to the contact portion 71 thereof. The other terminal lead is 50 connected, through the coupling member 65 and the lug 53, to the rivet 68, which serves the dual purpose of securing the lug in position and of serving as the switch contact. It is thus apparent that, upon actuation of the member 44 to bring 55 the plunger head 71 into contact with the surface 70, a current will be established through the filament 76 of the lamp, which will serve to light the lamp. Also, disengagement of the head 71 from the surface 70 will result in breaking of the circuit, which will result in extinguishment of the lamp. Only one switch contact need be used, therefore, and this switch contact also serves to hold the terminal lug in position.

The combination of the use of a rivet as a contact member, the rivet also being used for holding a terminal lug in position, together with the use of a plunger reciprocable with respect to the switch actuating member, and which is spring-pressed in such manner that the switch is positively held in either actuated or unactuated position, is believed to be broadly new. The combination, embodied in a switch structure of the type described, produces a switch which is small 70 in size, compact, has relatively few parts, there- 75

by reducing the possibility of any of the parts becoming loose due to vibration or jarring of the switch structure, and which can be economically and quickly manufactured and assembled into 5 position.

I do not intend to be limited to the specific details of construction shown in the preferred embodiment of my invention, but only in so far as defined by the scope and spirit of the appended 10 claims.

I claim:

1. In combination, a switch housing of generally rectangular shape having an open top and an open end, a switch lever pivoted 15 in the bottom wall of said housing for transverse swinging movement therein, an insulating closure plate over the top of said housing, a contact carried by said plate and projecting into said housing said contact being disposed in the path 20 of movement of said lever, and a terminal lug se-

cured by said contact to the outer surface of said plate and extending downwardly along a side wall of said housing, said lug having a terminal screw insulated from and projecting inwardly through an enlarged opening in the wall of said housing. 5

2. In combination, a box-like switch housing having two contiguous open sides, a switch lever pivoted intermediate its ends on a wall of said housing opposite one open side and swinging in a plane parallel to the other open side, a telescoping contact carried on the end of said lever within said housing, an insulating closure plate disposed over said one open side and carrying a contact disposed in the path of movement of said switch lever contact, and a terminal lug carried by said 15 contact on the external surface of said plate and having an end portion lying parallel to and insulated from the side walls of said housing.

MARION W. MORRIS. 20
